UNITED STATES PATENT OFFICE.

MERTON L. DODGE, OF SEATTLE, WASHINGTON, ASSIGNOR TO THE SEATTLE ASTORIA IRON WORKS, OF SEATTLE, WASHINGTON.

AUTOMATIC STOP FOR CAN-MAKING MACHINES.

Application filed February 6, 1923. Serial No. 617,397.

To all whom it may concern:

Be it known that I, MERTON L. DODGE, a citizen of the United States, and a resident of Seattle, King County, Washington, have 5 invented certain new and useful Improvements in Automatic Stops for Can-Making Machines, of which the following is a specification.

This invention relates to can making machines, and more particularly to improvements in the machine known in the can making art as the double seamer, and which operates to secure the ends of the cans to the body portion.

15 The principal object of this invention is to provide means for automatically stopping the double seamer should the can end feed mechanism embodied therein for any reason fail to function.

20 Other objects of the invention reside in the various details of construction and in the combination of parts embodied in the mechanism for accomplishing the above object.

25 In accomplishing these and other objects of the invention, I have provided the improved details of construction, the preferred forms of which are illustrated in the accompanying drawings, wherein—

30 Figure 1 shows a side elevation of a part of a machine equipped with mechanism embodied in the present invention.

Figure 2 is a sectional view, taken on the line 2—2 in Figure 1, illustrating the construction of the clutch control mechanism.

35 Figure 3 shows in plan view a part of the can end feed disk, and showing in a horizontal section, taken on line 3—3 in Figure 4, parts of the valve operating mechanism.

40 Figure 4 is a vertical, sectional view through the stop valve mechanism, taken on the line 4—4 in Figure 3.

Figure 5 is a horizontal section through the valve, taken on line 5—5 in Figure 4.

45 Figures 6 and 7 are similar views showing the valve in different positions.

Figure 8 is a side elevation, partly in section, of the stop and brake mechanism in normal position; the view being taken on the line 8—8 in Figure 2.

50 Figure 9 is a view of parts shown in Figure 8, showing the first step in the braking operations completed.

Figure 10 is a similar view showing the brake on, and clutch thrown out of engagement.

Figure 11 is a partial view of the brake mechanism, illustrating an alternative construction whereby the brake may be actuated electrically by utilizing a solenoid.

Figure 12 is a sectional view of a housing 60 and contact member used in the alternative construction in lieu of the valve mechanism.

Figures 13, 14, 15, and 16, are similar views, taken horizontally through the contact housing and showing different positions of the contact actuating and control members for different positions of the control levers.

Referring more in detail to the drawings, 1 designates, as a whole, a machine to which the present mechanism is applied, and 2 designates can bodies that are being moved into the machine by means of a belt 3 operating about a driven sprocket 30 and traveling in the direction indicated by the arrow adjacent thereto. Supported upon the frame of

the machine are vertical guide standards 4 wherein a stack of can ends 5 are supported, and which are fed, one at a time, by means of a reciprocating blade designated at 6, 80 from the lower end of the stack onto a circular table or disk 7, to be advanced to the clinching head of the machine by the fingers 8' of a turret 8, that is fixed on a vertical, revolvably driven shaft 9. In this machine the can bodies 2 are advanced after leaving belt 3 by a turret similar to turret 8 shown in Figure 3, and which is revolved also by shaft 9, and they are advanced in accordance with and directly beneath the covers 5 therefor.

During the operation of the machine, the covers or ends are picked up by a suction cup arrangement and are placed thereby upon the ends of the bodies 2 and are secured to the bodies by the double seamer device, not illustrated. Should the end feed device for any reason fail to operate, or should the body supply become exhausted and ends continue to be fed into the machine, without the present device damage to the parts would result and there would be a loss of time while parts were being readjusted and damaged bodies removed.

The means provided for automatically stopping the machine, should the feed device for any reason fail to function, comprises levers 10 and 11 that have ends fixed respectively to a tubular shaft 12 and a shaft 13 that is fitted revolvably therein. These shafts 105

110

are supported vertically by a bracket 14, formed as a part of a valve housing 25 and which is secured for vertical adjustment to the can guide table, or disk, 7, by a cap 16, as shown in Figures 3 and 4. At the swinging ends of levers 10 and 11 are rollers 17 and 18 that are adapted respectively to be simultaneously engaged by the can ends and can bodies as the latter are advanced, to thereby cause the levers to swing outwardly, as shown in dotted lines in Figure 3, and to thereby rotate their supporting shafts 12 and 13.

The levers are held yieldably in such position that their rollers will be engaged by the advancing ends and bodies by means of springs 15 and 15' that are secured to the lower ends of their respective shafts 12 and 13 and to the bracket 14 as shown in Figure 4.

Formed integral with the upper ends of shafts 12 and 13 are valves 19 and 20, (see Figures 4, 5, 6 and 7) of cylindrical form which are contained concentrically within the valve housing 25. The valve 20 is fitted rotatably within the valve 19 and the cover 25' of the housing has a hollow body 21 fitted within the valve 20. This hollow body is connected by a pipe 22 with a vacuum chamber, designated at 22', and has ports 23 and 23' at diametrically opposite points in its side walls. The construction and arrangement provides an air chamber 24 in the body 21 and an annular chamber 26 about the valve 19. The valve 19 is provided at opposite sides with ports 27-27' and valve 20 is provided at opposite sides with equally spaced pairs of ports 28-28', but the ports of these several parts normally are not in registration and no air connection is provided between chambers 24 and 26.

When the machine is operating normally, with can bodies and ends being advanced to the machine in proper relation, levers 10 and 11 will be engaged and moved simultaneously to rotate valves 19 and 20 within the valve housing but without changing their relation to each other and without making an air passage between chambers 24 and 26, but should a can body 2 pass under disk 7 when there is no end 5 above it, lower lever 11 will move valve 20 to the position shown in Figure 6, while valve 19 will remain still, thereby providing a passage from chamber 24 to chamber 26 by way of ports 23, 28, and 27 on one side, and ports 23', 28' and 27' on the other. Again, should an end be advanced into the machine with no can body below it, valve lever 10 will revolve valve 19 to position as shown in Figure 7, while valve 20 remains still, thereby making another connection between chambers 24 and 26.

The above described valve movement which provides connection between cham-

bers 24 and 26, effects the actuation of the brake and clutch mechanism whereby the machine is stopped.

Referring now to Figures 1 and 2, 31 designates the drive shaft of the machine. This has a pulley 32 revolvably mounted on it, which is driven by a belt 33, and which is operatively connected to drive the shaft through certain clutch mechanism presently described. On the shaft 31 is a worm 35 which drives a gear 36 on a vertical shaft 37, the latter being connected by a train of gears 38 with shaft 9 which revolves the can cover and body advancing turrets and advances belt 3.

The clutch and brake mechanism herein-after described may be manually operated by means of a horizontal lever 40, and is automatically operated to "off" position by the movement of a piston 41 in a cylinder 42. The cylinder is connected by pipe 43 with valve housing 25, and whenever the valves 19 and 20 are actuated so as to provide a connection between chambers 24 and 26, the piston will be actuated, by vacuum pressure, from position as shown in Figure 8, inwardly to position as shown in Figure 9.

The pulley 32 is provided on its inner face with a friction clutch surface 45 against which a friction disk 46 may be pressed to effect a driving connection with the shaft 31. The disk 46 has a hub portion that is slidably mounted upon a collar 47 that is fixed to the shaft 31 by means of a pin 48. A pair of levers 49 are pivotally supported by pins 50 from the disk body and these have their inner ends 51 extended into slots 52 in the collar 47 to provide a driving connection between the disk and the shaft.

A cone 54 is slidably mounted on the shaft 31 and may be shifted by movement of lever 40 to actuate the clutch. The cone is actuated by means of a pin 55 fixed in the lever and projecting into a groove 56 in the cone. The levers 49 have arms 57 provided with rollers 58 engaging the cone surface and when the latter is shifted outwardly it actuates these arms to move the levers in such manner as to press the clutch disk against the pulley to effect the driving of the shaft 31 and when the cone is moved inwardly, springs 59 between the outer ends of the levers and the disk permit the latter to release the disk from driving connection with the pulley. Fixed concentrically to the disk 46 is a brake drum 53 and fitted to this are upper and lower brake bands 61 and 62, respectively, having ends connected by a hinge pin 63 and provided at their other ends with shoes 64 and 65. Supported on a pivot pin 66 that extends from a bracket 67 fixed to the machine frame, is a bell crank lever 68 having a horizontal arm 69 and a vertical arm 75; the former being connected at its end by means of pivotally attached

links 70 with the shoe 65 of the lower brake band. Attached also to this arm is a bell crank lever 71 having a vertical arm 71' provided at its lower end with a slot 72 through which a link 73, that is fixed to the piston 41, extends. This link 73 has a pin 74 through its outer end to retain the slideable connection with the lever. The vertical arm 75 of the bell crank 68 is provided on its inner face with a lug 76 that is engageable with stop screws 77 and 78 that are adjustably mounted in the bracket 67, to limit the crank movement in opposite directions. This arm is connected by a link 80 with a 15 crank arm 81 extending from lever 40, so that the brake may be set or released manually by movement of the lever 40; the latter being pivotally mounted on a pivot pin 40' fixed in the upper end of bracket 67.

20 The lever 71 has a horizontal arm 83 with one end extended between the brake band shoes 64 and 65 and its other end forming a stop shoulder 85 that is extended to a position that it will be engaged by the upper face 25 of a lug 86 on the bell crank 68. An eye bolt 88 is fixed to the upper brake shoe 64 and extends downwardly and slidably through a pivot pin 89 carried by the inner end of the arm 83 of the lever 71 and downwardly 30 through a slot 90 in the brake shoes 65. A spring 91 is coiled about the lower end of bolt 88 to press upwardly against the pin 89 and against tension adjusting nuts 92 on the lower end of the bolt. A stop nut 93 adjustably mounted on the bolt 88 limits the 35 downward movement of the bolt through the pin 89.

Assuming that the parts are so constructed and assembled, and in normal position, as 40 shown in Figure 8, should the feed mechanism, previously described, fail to function so that the valve parts 19 and 20 are moved to effect a vacuum pressure connection between pipe 22 and the cylinder 42, the piston 41 will be actuated, and by its movement, 45 through connecting link 73, the lever 71 will be moved pivotally to a new position, as shown in Figure 9, and the arm 83 thereof will pull down on the upper brake band 50 through the medium of eye bolt 88 and spring 91, and will bring both brake bands into engagement with the brake drum. The drum will tend to rotate the brake bands with it and will thereby cause the links 70, 55 attached to both brake band 62 and bell crank 68, to rotate the crank 68 to the position as it is shown in Figure 10, and in doing so will move the lug 76 of the lever against the stop screw 78 which limits its travel and 60 forms a fixed anchor for the brake. The stop shoulder 85 on the arm 83 is thereby brought against lug 86, (Figure 10) and since the end of lever arm 83 is now in closer 65 relative position to the end of the lower brake band 65 than when in normal position,

(Figure 8) brake tension is held on the drum by tension of the spring 91. This tension may be regulated by adjustments of nuts 92 to any degree required for quickly or gradually stopping the machine. Also, as the 70 crank 68 is moved, it actuates lever 40, by means of connecting member 80, to release the clutch.

An adjusting arrangement to keep the 75 brake band from dragging on the drum is provided in a supporting set screw 100 in an arm 101 extended from bracket 67 and another set screw 102 in lever arm 71'. A spring 97 coiled about an eye bolt 95 that is fixed to the shoe 65 and which extends through a slot 96 in the arm 71', acts against the arm 71' to return the bracket to normal position immediately as the rotating motion of the brake stops, and set screw 102 will 80 adjust the bands with respect to the drum. This operation automatically stops the machine and as soon as the rotating motion of drum ceases, there being no vacuum holding piston 41 over as shown in Figure 9, spring 97 will draw levers 71 and shoe 65 back 85 together releasing brake, and automatically resetting all parts to normal position, shown in Figure 8, but does not throw the clutch back in for the reason that in the formation of the slot 80' in the link 80 enough clearance is provided that the parts may return 90 to normal position and the brake band released from the drum without causing resetting movement of the clutch. To start 95 machine after trouble has been remedied lever 40 is pulled over sliding cone 54 between rollers of levers 58 substantially as 100 described, beginning at line 105, page 2.

In Figures 11 to 16 inclusive, I have 105 illustrated an alternative mechanism whereby the same result, as just described can be accomplished by the use of an electric solenoid in place of the cylinder and piston, and by using electric contacts in place of the valves 19 and 20 for closing a circuit 110 through the solenoid.

In this construction the link 73 would be 115 connected to the armature 105 of the solenoid 106, and the latter connected with a source of electricity by means of wires 107 and 108. Within the base of the housing 25 is placed a block of insulation 109 upon which two plates 110, 111 are fixed and which are connected electrically with wires 112 and 113 for closing a circuit through 120 the solenoid from a source of electricity. Supported from the ends of plate 110 are circularly formed segmented bands 114 and 115, and opposite thereto are segments 116 and 117 secured to the ends of plate 111. Supported by posts 118 and 119 that are 125 mounted to extend upwardly between plates 110-111 are semi-circular contacts 120 and 121, the ends of the former being adapted to be pressed into contact with bands 114 and 130

116, and the ends of the latter likewise being adapted to be pressed into contact with bands 115 and 117 which, in either case, would close a circuit through the solenoid 5 to actuate the armature inwardly to stop the machine.

In place of the valve mechanism described in connection with the other mechanism, means are provided on shafts 12 and 13 for 10 closing the circuit, and this consists of collars 125 and 126 fixed respectively to the upper ends of the shafts and which support contact blocks 127 and 128 of a non-conductive character which are for the purpose of 15 pressing the ends of contact segments 120 and 121 into circuit closing contact with segments 114, 115, 116, and 117.

When the machine is operating normally the blocks are positioned as shown in Figure 13, and when the levers 10 and 11 are 20 engaged by the can ends and bodies, the shafts rotate together and move the blocks to position as shown in Figure 14, still leaving the circuit to the solenoid open. But 25 should the can end feed fail and a body pass into the machine without an end therefor, shaft 13 will be actuated while shaft 12 remains still and this would cause the block 128 to be removed to position, as shown 30 in Figure 15, to press end of contact band 120 against contact 116 to thereby close the circuit through the solenoid to stop the machine. Likewise, should a can end pass into 35 the machine without a body therefor, the shaft 12 will be rotated while shaft 13 remains still, and this will cause block 127 to engage contact segment 121 to press it into circuit closing contact with plate 115, as shown in Figure 16, to close the circuit 40 through the solenoid to stop the machine.

It is readily apparent that with the mechanism illustrated the stopping operation is entirely automatic and parts will be automatically reset after the machine has been 45 stopped by means of spring 97. The mechanism in no way prevents manual operation by use of lever 40.

Having thus described my invention, what I claim as new therein and desire to secure 50 by Letters-Patent is:

1. In a machine of the class described, the combination with means for advancing can bodies and ends into the machine and brake mechanism operable to stop the same, 55 of yieldable members positioned to be engaged and moved respectively by can bodies and ends as advanced and mechanism under control of said members operable to actuate the brake mechanism.

2. In a machine of the class described, the combination with means for advancing can bodies and can ends into the machine and brake mechanism operable to stop the same, 60 of yieldable members positioned to be simultaneously engaged respectively by can

ends and bodies when advanced into the machine and means under the control of said members for actuating the brake if either is actuated individually.

3. In a machine of the class described, 70 the combination with means for advancing can bodies and ends into the machine and a brake mechanism operable to stop the same, of an air cylinder, a piston in the cylinder operatively connected to actuate the brake mechanism, a source of pressure, a conduit connecting said source and cylinder, a normally closed valve mechanism in said conduit and yieldable members positioned to be simultaneously engaged by can ends and 80 bodies delivered into the machine, operably connected with the valve mechanism whereby the valve will be opened if either of said members is moved individually.

4. In a machine of the class described, the 85 combination with means for advancing can bodies and ends therefor into the machine, a brake and clutch mechanism operable to stop the same, and a vacuum pressure source, of a cylinder, a piston in the cylinder operatively connected to actuate the brake and clutch from driving to "off" position, a conduit connecting the cylinder with the vacuum source, a valve mechanism connected in the conduit and normally closing the 90 same, a pair of yieldably supported levers positioned to be engaged and moved simultaneously by can ends and bodies delivered into the machine and operatively connected 95 with the valve mechanism to cause the latter to be opened, should either lever be moved individually, to thereby effect actuation of the piston, and automatic means for resetting the brake and valve parts. 100

5. In a machine of the class described, the 105 combination with means for advancing can bodies and ends therefor into the machine and mechanism operable to stop the same, of a cylinder, a piston in the cylinder operatively connected to actuate the stop mechanism, a source of pressure, conduits connecting the source of pressure with the cylinder, a valve mechanism normally closing the connection, comprising two relatively movable valve members adapted if moved individually to effect the opening of the valve, a shaft for actuating each of said movable members, levers fixed to said shafts and extended to be simultaneously engaged and moved by can bodies and ends as advanced 110 into the machine. 115

6. In a machine of the class described, the combination with means for advancing can bodies and ends therefor into the machine, and mechanism operable to stop the same, of a cylinder, a piston movable in the cylinder and operatively connected to actuate the stop mechanism, a source of pressure and conduits connecting the said source and cylinder, a valve mechanism connected in 120 125 130

the conduits to normally close the same comprising central and outer chambers, a pair of relatively movable valve members between the said chambers having normally 5 non-registering ports, an actuating shaft for each of said valve members, lever arms fixed to said shafts and extended within the paths of can ends and bodies advanced into the machine whereby movement of one member 10 without like movement of the other will move the ports of the valve members into registration to open the valve and effect actuation of the piston.

7. In a machine of the class described, the 15 combination with a source of pressure medium, means for advancing can bodies and ends therefor into the machine and brake mechanism operable by said pressure medium to stop the machine, of a control mechanism 20 for the pressure medium comprising a valve housing having a ported central chamber connected with the pressure medium source and an outer chamber connected with the brake actuating mechanism, a pair 25 of valves fitted one upon the other about the said central chamber normally closing its ports, and having normally non-registering ports therein, a shaft for rotating each of said valves, lever arms fixed to said 30 shafts and extended in position to be actuated by can ends and bodies advanced into the machine and whereby if either is actuated individually, ports are brought into registration to effect a connection between 35 the valve chambers.

8. In a machine of the class described, the combination with means for advancing can ends and bodies into the machine, a stop mechanism therefor, and a source of pressure medium having a connection with the stop mechanism, of a control device comprising a supporting bracket and an integral housing forming an outer valve chamber, a cover for the housing forming a central 45 valve chamber connected with the source of pressure medium and having outlet ports, a tubular shaft rotatably supported in the bracket and extended into the housing, another shaft rotatable within the tubular 50 shaft, valves fixed to said shafts and fitted one to the other and to the central valve chamber and normally closing the ports of the latter, a pair of lever arms fixed to said shafts and extended into the paths of can 55 bodies and ends advanced into the machine to be actuated thereby to revolvably move the valves, said valves being provided with normally non-registerable ports adapted to be moved into registration by individual action 60 of either lever to thereby open the valve but to retain their relative closed relation if actuated together, and yieldable means fixed to the shaft and bracket for returning the parts to normal position.

9. In a machine of the class described, the

combination with means adapted for the synchronous feeding of can bodies and ends therefor into the machine and a normally connected driving mechanism for the machine, of an automatic stop mechanism comprising co-operating members operable respectively under the control of the can bodies and can ends as delivered into the machine and adapted to effect the stopping of the machine by a disconnection of the driving mechanism should there be any disturbance in the synchronous feeding of the said bodies and ends into the machine.

10. In a machine of the character described, the combination with means adapted for the synchronous feeding of can bodies and ends therefor into the machine, a driving clutch and a brake mechanism, of a source of pressure medium, a stopping mechanism connected with and adapted to be influenced by the admittance thereinto of said pressure medium to set the brake and to release the clutch, and a pressure medium control valve comprising parts disposed to be engaged by the bodies and ends fed into the machine and to be so actuated incidental to any disturbance in the synchronous feeding of the bodies and ends as to thereby admit pressure medium to the stopping mechanism.

11. In a machine of the character described, the combination with means adapted for the synchronous feeding of can bodies and ends therefor into the machine, a driving clutch and a brake mechanism, of a source of pressure medium, a stopping mechanism connected with and adapted to be influenced by the admittance thereinto of said pressure medium to set the brake and to release the clutch, and a pressure medium control valve comprising parts disposed to be engaged by the bodies and ends fed into the machine and to be so actuated incidental to any disturbance in the synchronous feeding of the bodies and ends as to thereby admit pressure medium to the stopping mechanism, and manually operable means for resetting the clutch.

12. In a machine of the class described, the combination with driving means for advancing can bodies and ends therefor into the machine, a clutch mechanism, a brake drum, and a brake setting device operable upon the discontinuance of feed of can bodies or ends, of a brake for the drum operatively connected with the setting device and adapted to be moved rotatably with the drum when actuated to braking contact, a pivotally supported bell crank lever having one arm operatively connected with the brake whereby such rotatable movement of the latter will move the crank pivotally, and having its other arm connected to release the clutch by such pivotal movement.

13. In a machine of the class described, the combination with means for feeding can bodies and ends into the machine, a driving clutch for the said means movable between 5 "on" and "off" positions, a brake drum, and a brake setting device operable by a discontinuance of the delivery of can ends or bodies into the machine, of a brake band for the drum adapted to be clamped there- 10 against by the setting device and to move rotatably with the drum when set, a pair of spaced stop members, a pivotally supported bell crank lever having one arm operatively connected to actuate the clutch to "off" po- 15 sition and having its other arm operatively connected with the brake band and setting device, said crank being pivotally movable by rotative movement of the brake band and having a stop lug thereon engageable 20 with said stops to limit its movement.
14. In a machine of the class described, the combination with means for advancing can bodies and ends into the machine, a clutch mechanism, a brake drum, and a 25 brake setting device operable under the control of can ends and bodies delivered into the machine, of a brake band for the drum adapted to be rotated a limited distance with the drum when brought 30 into braking contact therewith, a pivotally mounted bell crank lever, another bell crank lever having an arm pivotally supported from one arm of the first bell crank and operatively connected for actuating the brake band, and its other arm connected with the brake setting device, and means operatively connecting the first bell crank with the clutch mechanism whereby movement of the crank incidental to the 35 brake band movement releases the clutch. 40
15. In a machine of the class described, the combination with a drive shaft, a clutch on the shaft, a brake drum and a brake setting device under the control of can parts delivered into the machine, of a brake band 45 for the drum, a pair of spaced apart stops, a pivotally mounted bell crank lever having a vertical and horizontal arm, and provided with a stop lug engageable with said spaced stops to limit its pivotal movement, 50 means connecting the vertical arm actuating the clutch, a link connecting the end of horizontal arm of said lever with the free end of the lower brake band, a second bell crank having a vertical arm connected with the brake setting device, and a horizontal arm pivotally connected between its ends with the horizontal arm of the first lever and at its end having a yieldable connection with the free end of the brake band. 55 60

Signed at Seattle, Washington, this 19th day of January, 1923.
